UNITED STATES PATENT OFFICE.

NICOLAS EMILIE MÉTHLIN, OF PARIS, FRANCE, ASSIGNOR TO SCHNEIDER & CIE, OF PARIS, FRANCE, A LIMITED JOINT-STOCK COMPANY OF FRANCE.

MUZZLE COVER FOR GUNS.

Application filed October 15, 1927, Serial No. 226,356, and in France December 18, 1926.

The present invention relates to a muzzle cover more particularly applicable to guns mounted on board submersible or other craft, such as torpedo boats, in which the chase is 5 most frequently, when the gun is not in action, withdrawn into a lowered position which is horizontal or approaching the horizontal, the bore of the gun barrel being then, even when it is not the case of a ship intended 10 to navigate under water, out of reach of the sea water.

The invention consists essentially in a closing member mounted in a fixed position and connected to a mechanism, the movements of 15 which for closing the gun and opening the latter are controlled by the lowering movements of the gun into a determined position and the upward movements of the gun starting from this same position.

20 Two embodiments of the invention are illustrated by way of example in the accompanying drawing.

Fig. 1 is a sectional elevation of a muzzle cover constructed according to the invention 25 and mounted for example upon the resisting hull of a submersible craft, the parts of the device being shown in the position they occupy until the moment when the chase, during its lowering movement, acts upon it in 30 order to bring the closing member into the position of closure.

Fig. 2 is a similar section showing the members moved into this position.

Fig. 3 is a side elevation viewed from the 35 left in Fig. 2 with the chase of the gun shown in dot and dash lines.

Figs. 4, 5 and 6 are views corresponding to Figs. 1, 2 and 3 and illustrate a modification.

The muzzle cover or closing member proper 40 A is carried by a movable support B, which forms a stop by means of a boss b of suitable profile as in the example shown in Figs. 1 to 3, or by a roller b as in the example shown in Figs. 4, 5 and 6, for the chase when the latter reaches a determined position near the lowered or withdrawn position. The closing member support B, to which the closing member proper A may be rigidly secured or in which it may take a limited longitudinal 45 displacement, is subjected to the action of a spring C which tends constantly to hold the closing member in the position it occupies when the muzzle is opened for raising the gun barrel.

50 In the example shown in Figs. 1 to 3, the

closing member proper A is rigidly secured to the closing member support B, which is pivotally mounted upon a shaft D¹ carried by the support D, which forms a lodgment for the lifting spring C. In practice the spring C 60 will be covered by a reversed socket C¹ provided with a projecting pin C² movable in a slot d, which limits the lifting movement of the closing member support B which is provided with a corresponding boss b¹ adapted 65 to engage a lug or boss d¹ provided on the support D whereby pivotal movement of said support away from closing position is positively limited.

When the members are in the position of 70 origin shown in Fig. 1, if the chase E of the gun barrel in the movement of withdrawal comes into contact with the boss b, which itself bears upon the socket C¹ it lowers, by the continuation of this downward movement, 75 the closing member support B which pivots about the shaft D¹ and thus at the end of the travel of the chase, presses the packing a of the closing member proper against the front face of the gun barrel.

80 Inversely, when the chase E is raised, the spring C, through the medium of the socket C¹, raises the closing member support B—A and returns it from the position shown in Figs. 2 and 3 into that shown in Fig. 1.

In the example shown in Figs. 4 to 6, the closing member support B is rigid with the rod B² of the piston B¹ upon which acts the lifting spring C, which bears at one end upon the end of the fixed support D. The closing 90 member A is guided by a rod A¹ in the support B, in which this rod is adapted to move longitudinally, and by a roller A² forming a slider in a slideway D³ formed in an arm D² rigid with the fixed support D.

95 When, during the disappearing movement, the chase E presses upon the roller b, it lowers the support B, compressing the spring C and, as the roller A², during the downward movement of the support D is compelled to move in the slideway D³, it displaces by means of the rod A¹ the closing member A, which it carries so as to bring the joint packing a, at the end of the disappearing movement into contact with the front face of the 100 chase, as shown in Fig. 5.

105 When, on the other hand, the chase E is raised, the spring C raises the arrangement B¹—B²—B and carries with it in this lifting movement, the arrangement A—A¹—A².

110

As the roller A² is compelled to follow the slide D³, it brings, at the end of its travel, the closing member proper into the position shown in Fig. 4.

5 The automatic device described, which ensures the automatic closure of the muzzle, presents in addition the advantage of provoking its automatic opening for firing, and of thus making it impossible to forget to remove the 10 muzzle cover and avoiding the serious consequences (the bursting of a projectile in the bore of the gun barrel) which such an omission would cause.

I claim:

15 1. In combination, a fixed support, a closure member for the muzzle of a gun movably mounted on said support, resilient means carried by the support, and means having operative engagement with the resilient means and

20 closure member for moving the latter to non-closing position, the closure member being moved to closed position by movement of the gun in engagement with said last-named means.

25 2. Apparatus for closing the muzzle of a gun comprising a fixed support, a member movably mounted on said support, a closing member carried by the movably mounted member, and yielding means for normally maintaining the closing member in non-closing position, said movable member being adapted to be engaged by the gun whereby movement of the gun is effective to move the closing member to closing position.

30 35 3. In apparatus for closing the muzzle of a gun, a fixed support mounted adjacent the muzzle of the gun, a movable support carried by the fixed support, a closing member carried by the movable support and adapted to engage the muzzle of the gun, and yielding means for moving said movable support and closing member to non-closing position, said movable support being adapted to be actuated by the gun to move the closing member to closing position.

40 45 4. In apparatus of the class described, a fixed support, a member slideable in said support, yielding means carried by the support and having engagement with said slideable means, a closing member for the muzzle of the gun, and means for mounting said closing

member, said last named means having engagement with said slidably mounted member and being positioned for engagement with the gun.

5 55 60 65 70 75 80 85 90 95 5 In apparatus of the class described, a fixed support mounted adjacent the muzzle of the gun, resilient means carried by said support, a member having telescopic engagement with said support and resilient means, a movable support carried by the fixed support and having a portion adapted to engage the telescopic member, and a closing member carried by the movable support for engaging and closing the muzzle of the gun, said closing member being adapted to be moved by said resilient means to non-closing position and also being adapted to be moved to closing position by movement of the gun in engagement with said movable support.

6 In apparatus of the class described, a fixed support, a movable support operatively connected to the fixed support, a closing member carried by the movable support and having a portion adapted to be engaged by a gun, and resilient means for moving the closing member to non-closing position, the closing member being adapted for movement to closed position by engagement of the gun with the movable support.

7 75 80 85 90 95 5 In apparatus of the class described, a closing member for the muzzle of a gun, means for movably mounting said closing member adjacent the gun muzzle, and means for moving said closing member to a non-closing position, said first named means being adapted for engagement with the gun whereby the gun is effective to move the closing member to closing position.

8 In combination with a gun, a closing member for the muzzle of the gun, means movably mounting said closing member, and yielding means adapted for engagement with the mounting means whereby the closing member is moved to non-closing position, said gun being adapted to engage the mounting means whereby the closing member is moved into engagement with the muzzle of the gun.

In testimony whereof I have signed this specification.

NICOLAS EMILIEN METHLIN.
